CLAIM

We claim the ornamental design for an upper frame for an off-road vehicle, as shown and described.

DESCRIPTION

FIG. 1 is a front and left side perspective view of an upper frame for an off-road vehicle embodying our new design; FIG. 2 is a front elevation view thereof; FIG. 3 is a rear elevation thereof; FIG. 4 is a top plan view thereof; FIG. 5 is a bottom plan view thereof; FIG. 6 is a right side elevation view thereof; and, FIG. 7 is a left side elevation view thereof. The portions of the upper frame for the off-road vehicle shown in broken lines form no part of the claimed design.
